UNITED STATES PATENT OFFICE.

GEROME F. TADINI, OF NEW YORK, N. Y.

FIRE-ESCAPE.

1,249,243.

Specification of Letters Patent. Patented Dec. 4, 1917.

Application filed June 25, 1917. Serial No. 176,713.

To all whom it may concern:

Be it known that I, GEROME F. TADINI, a citizen of the United States, residing in the borough of Manhattan, city, county, and 5 State of New York, have invented an Improvement in Fire-Escapes, of which the following is the specification.

This invention relates to a fire escape apparatus and more particularly to that form 10 of fire escape which may be raised and lowered in the operation thereof so as to be brought to a level with any floor of the building to which the fire escape is attached, and after the persons desiring to leave the 15 building are on the fire escape it may be lowered to the ground or a position of safety, suitable means being employed for controlling the operation of the apparatus.

In carrying out the present invention I 20 preferably employ a suitable platform for the apparatus together with a plurality of upright guide and support members suitably attached to the building and in which the control members are contained, these control 25 members being connected to the fire escape and operated thereon by suitable devices to engage the guide supports and to be released so as to either grip the guide supports to maintain the fire escape in position or to 30 permit the fire escape to be raised or lowered as occasion may require. The fire escape is also provided with suitable counterweights so that normally it may be maintained in any desired position and with control ropes 35 by which it may be raised and lowered either from the platform of the fire escape or from any window or opening in the building adjacent the line of the control ropes. The apparatus made in accordance with this invention 40 will be hereinafter more particularly described in connection with the accompanying drawings in which:

Figure 1 is a general front elevation of the apparatus comprising my invention.

Fig. 2 is an end view and partial cross section on an enlarged scale.

Fig. 3 is a cross section on line 3—3 Fig. 2, and

Fig. 4 is a cross section on the parts shown 50 in Fig. 3 taken at right angles thereto.

Referring to the drawing, in carrying out my invention, I employ a fire escape comprising a platform 10 fitted with a front 11 and side members 12 and 13. These parts 55 may be made of any suitable material and connected in any desired manner. The side

members are similar and consequently but one side member will be described. Each side member terminates in brackets 14 and 15 having cylindrical ends which fit and are 60 adapted to slide within tubular guide supports 16 which are split at 17 longitudinally so as to receive the portions of the side members adjacent the cylindrical ends, and these tubular guide supports are secured in up- 65 right positions and in any suitable manner to the side of the building to which the fire escape is to be attached. Each cylindrical end of the brackets is the same and consequently but one of these members will be described in detail. For example, the cylindrical end of the bracket 14 is centrally of reduced diameter as indicated at 18 and adapted to receive a split ring 19 which, as 70 will be understood, also fits within the corresponding tubular guide support. With each split ring there is employed an arbor, one end 20 of which is journaled in the upright member 21 in the corresponding bracket while the other end 22 is journaled 75 in a bearing provided therefor in the reduced portion of the cylindrical end of the bracket. Each arbor carries a rectangular block 23 lying between the split portion of the ring 19 and adapted as will be understood, when 80 the arbor is turned, to act as a cam, the opposite corners bearing against the edges of the split ring to force the same apart and against the walls of the tubular guide support. On each of these arbors there is also 85 an arm 24. The arms 24 on one side of the apparatus are connected by a link 25 as shown in Fig. 1 of the drawing.

At the rear of the fire escape there is a frame comprising cross bars 26 and centrally 90 disposed and spaced uprights 27, these latter members being connected by a strap piece 28. Suitably journaled in the strap piece 28 and the lower cross bar 26, there is a shaft 29. On the lower end of the shaft 29 there 95 is a hand wheel 30 and also on the shaft 29 and immediately above the strap piece 28 or in any other suitable position, there is a second hand wheel 31. The upper end of the shaft 29 is screw threaded as indicated at 100 32 and adapted to operate in the tapped end of a socket member 33. This socket member 33 is pivotally connected to a lever bar 34 as indicated at 35. This lever bar extends 105 across the outermost tubular guide supports and at one end is pivotally connected to the link 25 while at the opposite end it is piv-

totally connected to a link 36 which corresponds to the link 25 and therefore is pivotally connected to the operating arms at the opposite side of the apparatus. I may also employ springs 37 and 38 or other suitable devices for equalizing the action of the lever bar 34 on the opposite ends thereof so that the tension when applied to the split rings will be the same on both sides of the apparatus.

10 Adjacent the top of the building in fitting the fire escape for use I employ pulleys 39 and 40 over each pair of which a rope or cable 41 passes and is provided at one end 15 on the exterior of the building with an eye 42 adapted to be engaged by a hook 43 secured in the upper face of the cylindrical end of the bracket 15 within the corresponding tubular guide support. At the other end 20 each rope or cable 41 is fitted with a counterweight 44, it being understood that there is preferably employed a counterweight on each side of the apparatus.

25 In order that the fire escape may be raised and lowered from the platform thereof or from a window in the building to which it is applied, I also employ a set of control ropes 45 each passing over pulleys 46 secured adjacent the top of the building, and 30 pulleys 47 secured adjacent the bottom of the building both on the outer surface thereof, and these control ropes also pass through the upper ends 48 of the upright members 27, and are preferably tied therein as indicated at 49. In the bottom of each tubular 35 guide support member I may also employ a spring 50 or other similar device to act as a cushion to absorb the shock if for any reason the fire escape should be brought down 40 suddenly to the lower limit of its travel.

45 From the foregoing description it will be apparent that the fire escape made in accordance with my present invention being counterbalanced will when released, be adapted to stay in any position in which it may be put and normally the parts are released so that by the use of the control ropes 45 the platform may be raised or lowered to any desired position, and when in a required position, the shaft 29 is turned through either 50 of the hand wheels 30 or 31 so as to raise the socket member 33 and consequently lift the lever bar 34. This movement of the lever bar raises the links 25 and 36 so as to swing 55 upwardly the arms 24 thereby causing the rectangular block members 23 to act as cams against the edges of the split rings 19 forcing the same to bind against the inner walls of the tubular guide supports. As will also 60 be understood, this action may be sufficient to cause the fire escape to descend at any desired speed when loaded, or if necessary to grip the same in a fixed position.

I claim as my invention:

65 1. A fire-escape apparatus comprising a

platform, a plurality of tubular guide supports, cylindrical members each having a circumferential recess therein and movable in said tubular guide supports, brackets for supporting the said platform and connected 70 to the said cylindrical members, devices lying within the circumferential recesses of the cylindrical members, and means actuated from the platform for operating said devices to cause the same to engage the inner circular surface of the said tubular guide supports.

2. A fire-escape apparatus comprising a platform, a plurality of split tubular guide supports secured to a building, recessed cylindrical members fitting and adapted to slide within the said split tubular guide supports, split rings lying within the recessed portions of the said cylindrical members, and means operated from the platform for actuating the said split rings to cause the same to engage the inner surfaces of the said split tubular guide supports.

3. A fire escape apparatus comprising a platform, a plurality of split tubular guide supports secured to a building, brackets having cylindrical ends fitting within the said tubular guide supports and connected to the said platform, each of the said cylindrical ends having a reduced portion therein, a split ring fitting within the reduced portion of each of the cylindrical ends of said brackets, a rectangular block lying within the split portion of each ring, an arbor journaled in each bracket and carrying the corresponding rectangular block, and means operative from the platform for turning the said arbors to cause the rectangular blocks to spread the split rings and bind the same to the tubular guide supports.

4. A fire escape apparatus comprising a platform, a plurality of split tubular guide supports secured to a building, brackets having cylindrical ends fitting within the said tubular guide supports and connected to the said platform, each of the said cylindrical ends having a reduced portion therein, a split ring fitting within the reduced portion of each of the cylindrical ends of said brackets, a rectangular block lying within the split portion of each ring, an arbor journaled in each bracket and carrying the corresponding rectangular block, an arm carried by each of said arbors, links connecting the said arms extending from corresponding tubular guide supports, a lever bar extending across the said tubular guide supports and connected at its ends to the said links, and means for raising and lowering the said lever bar to actuate the said arms and arbors to cause the said rectangular blocks thereon to spread the split rings in order to engage the tubular guide supports.

5. A fire escape apparatus comprising a platform, a plurality of split tubular guide

supports secured to a building, brackets having cylindrical ends fitting within the said tubular guide supports and connected to the said platform, each of the said cylindrical ends having a reduced portion therein, a split ring fitting within the reduced portion of each of the cylindrical ends of said brackets, a rectangular block lying within the split portion of each ring, an arbor 5 journaled in each bracket and carrying the corresponding rectangular block, an arm carried by each of said arbors, links connecting the said arms extending from corresponding tubular guide supports, a lever bar 10 extending across the said tubular guide supports, and connected at its ends to the said links, a shaft journaled in the platform frame and screw threaded at one end, a socket member adapted to be engaged by the screw threaded end of the said shaft and pivotally connected to the said lever bar, 15 and means for turning the said shaft, 20 extending across the said tubular guide supports secured to a building, brackets having cylindrical ends fitting within the said tubular guide supports and connected 25 to the said platform, each of the said cylindrical ends having a reduced portion therein, a split ring fitting within the reduced portion of each of the cylindrical ends of said brackets, a rectangular block lying within the split portion of each ring, an arbor journaled in each bracket and carrying the corresponding rectangular block, an arm carried by each of said arbors, links connecting the said arms extending from corresponding tubular guide supports, a lever bar 30 extending across the said tubular guide supports and connected at its ends to the said links, a shaft journaled in the platform frame and screw threaded at one end, a socket member adapted to be engaged by the screw threaded end of the said shaft and pivotally connected to the said lever bar, 35 means for turning the said shaft, counterweights by which the platform may be maintained in any desired position when the split rings are released, and control cables for raising and lowering the platform when 40 the split rings are released.

6. A fire escape apparatus comprising a platform, a plurality of split tubular guide supports secured to a building, brackets having cylindrical ends fitting within the said tubular guide supports and connected

to the said platform, each of the said cylindrical ends having a reduced portion therein, a split ring fitting within the reduced portion of each of the cylindrical ends of said brackets, a rectangular block lying within the split portion of each ring, an arbor journaled in each bracket and carrying the corresponding rectangular block, an arm carried by each of said arbors, links connecting the said arms extending from corresponding tubular guide supports, a lever bar 45 extending across the said tubular guide supports and connected at its ends to the said links, a shaft journaled in the platform frame and screw threaded at one end, a socket member adapted to be engaged by the screw threaded end of the said shaft and pivotally connected to the said lever bar, 50 means for turning the said shaft, counterweights by which the platform may be maintained in any desired position when the split rings are released, and control cables for raising and lowering the platform when the split rings are released.

Signed by me this 19th day of April, 1917.

GEROME F. TADINI.
